UNITED STATES PATENT OFFICE.

FRANKLIN O. ANDREWS, OF WILLOUGHBY, OHIO.

SCREW MACHINE.

Application filed January 29, 1921. Serial No. 440,877.

The invention relates particularly to machines for receiving bolt or other similar blanks and cutting screw threads thereon although in some aspects it is not limited to 5 a machine for such specific use.

One embodiment of the invention includes a pair of oppositely disposed, aligned, rotating and reciprocating thread cutting die heads. Means for automatically causing the 10 various movements of the die heads as well as for opening and closing them may be provided. Associated with the die heads is a mechanism for bringing blanks into alignment with them and stopping or holding the 15 blanks in such a position that they may be properly operated on by the dies. The blank carrier may consist of a disc rotatably mounted so that one point in its circumference is always in alignment with the die 20 heads. Means may be provided to give to the disc a step by step movement such that it will present blanks seriatim to the die heads. Means may be provided for locking the disc against rotation when blanks are 25 being operated on. Means, independent of the disc, or co-operating therewith, if desired, or found necessary, may also be provided for grasping and holding the blanks when they are engaged by the die heads. 30 Seats for the blanks may be provided in the feeding disc which in and of themselves may hold the blanks against rotation when attacked by the die heads.

For the purpose of fully disclosing the 35 nature and advantages of the invention a specific embodiment thereof will be described as illustrated in the accompanying drawings. It should be understood, however, that the invention is capable of various 40 modifications and, therefore, it is not limited to the particular structures illustrated.

In the accompanying drawings, Figure 1 is a plan view of the machine; Fig. 2 is a side elevation of the machine from the bottom of Fig. 1; Fig. 3 is an end elevation from the right of Fig. 1; Fig. 4 is a vertical transverse section on the line 4-4 of Fig. 1; Fig. 5 is a vertical transverse section on the line 5-5 of Fig. 1; Fig. 6 is a detail view of 45 a part of the mechanism for moving the blank carrier; Fig. 7 is a fragmentary side elevation of the blank carrier; Figs. 8 and 9 are perspective views in details of the blank carrier; Fig. 10 is a transverse section on the line 10-10 of Fig. 7; Fig. 11 is a transverse section on the line 11-11 of Fig.

7; Fig. 12 is a side elevation of a finished bolt; Fig. 13 is an end elevation of a finished bolt; Fig. 14 is a fragmentary side elevation of an optional form of blank carrier for conveying bolts in pairs; Fig. 15 is a transverse section through the carrier on the line 15-15 in Fig. 14 and Fig. 16 is a plan view of a fragment of the carrier shown in Fig. 14.

The machine is supported on legs 1 which carry a drive shaft 2 which may be driven in any suitable manner. In the present instance a pulley 3 is illustrated over which may pass a driving belt. The drive shaft 2 carries belt pulleys 4 and 5, the belts of which extend upwards through suitable holes in a bed plate 6. Supported on the bed plate 6 are end frames 7 and 8. Connected to the end frame 7 by bracing bars 9 is an intermediate upright frame 10. Connected to the end frame 8 by bracing bars 11 is an intermediate upright frame 12.

Rotatably mounted longitudinally on the machine in the upper ends of the frames 7 and 10 is a die shaft 13 carrying a pulley 14 through which the shaft may be rotated by a belt 15 from the pulley 4. Rotatably mounted longitudinally on the machine in the upper ends of the plates 8 and 12 is a die shaft 16 carrying a pulley 17 through which the shaft may be rotated by a belt 18 from the pulley 5. The shafts 13 and 16 are mounted so as to slide longitudinally in their bearings carrying with them the various mechanisms mounted on the shafts. The shafts 13 and 16 are on opposite ends of the machine and are in alignment with each other. At the innermost end of the shaft 13 is mounted a thread cutting die head 19. On the innermost end of the shaft 16 is mounted a thread cutting die head 20. In the present instance, for the purposes of illustration, these die heads are shown as of the well known Landis type. Any other type of thread cutting head might be substituted or pointer heads may be applied to the shafts 13 and 16.

Parallel with the shafts 13 and 16 is a cam shaft 21 extending throughout the entire length of the machine. The cam shaft 21 may be rotated from the die shaft 16 through a train of gears 22.

A face cam 23 mounted on the cam shaft 21 engages one arm 24 on a transverse shaft 25 pivoted on the bracing bars 11. Another arm 26 on the shaft 25 engages a collar on the die shaft 16, so that as the cam 23 ro-

tates it will tend to force the die head 20 carried by the die shaft 16 away from the center of the machine. A downwardly extending tail piece 27 on the shaft 25 is engaged by a spring 28 fastened to a projection 29 on the bed 6. This tends to hold the arm 24 against the cam 23 and consequently tends to force the die head 20 toward the center of the machine when allowed by the cam. A lever 30 engaging the usual collar for opening and closing the cutters in the head 20 is pivoted on the frame 12 and rides between a spring 31 and the stop nuts 32 on a pin 33 projecting from the frame 12 so as to open and close the die head 20 and limit the amount of threads cut as the die head 20 reciprocates.

A face cam 34 mounted on the cam shaft 21 engages one arm 35 of a transverse shaft 36 pivoted on the bracing bars 9. Another arm 37 on the shaft 36 engages a collar on the die shaft 13, so that as the cam 34 rotates it will tend to force the die head 19 carried by the die shaft 13 away from the center of the machine. A downwardly extending tail piece 38 on the shaft 36 is engaged by a spring 39 fastened to a projection 40 on the bed 6. This tends to hold the arm 35 against the cam 34 and consequently tends to force the die head 19 toward the center of the machine as allowed by the cam. A lever 41 engaging the usual collar for opening and closing the cutters in the head 19 is pivoted on the frame 10 and rides between a spring 42 and the stop nuts 43 on a pin 44 projecting from the frame 10 so as to open and close the die head 19 and limit the amount of threads cut as the die head 19 reciprocates.

Extending beyond the end frame 8 the cam shaft 21 carries a cam 45 which engages the upper end of an arm 46 pivoted on a pin 47 extending from the end frame 8. A link 48 extends from the arm 46 to the upper projecting arm 49 of a locking lever 50 pivoted on the end frame 8. The lower arm 51 of the locking lever 50 has a spring 52 fastened to the end frame 8. This tends to hold the locking lever 50 in one of the recesses of an index plate 53 on a shaft 54 rotatably mounted in the frames 7 and 8 and extending throughout the length of the machine.

Associated with the cam 45 is a cam 55 adjustable with relation to the cam 45 through a slot 56 which may be locked by a cap screw 57 tapped into the cam 45. The cam 55 engages one arm 58 of a lever mounted on the pin 47 which has a downwardly projecting arm 59 engaged by a spring 60 fastened to a projection 61 rising from the bed plate 6. This tends to hold the arm 58 against the cam 55. A pin 62 on the arm 58 is engaged by a slot in the end of a link 63 extending to an arm 64 rotatably mounted on the shaft 54 adjacent the index plate

53. The arm 64 carries a pivoted pawl 65 tending to engage a slot in the index plate 53. A spring 66 tends to keep the pin 62 seated in the bottom of the slot in the link 63 but allows sufficient freedom of movement to avoid damage or breakage in emergencies. The cams 45 and 55 are so adjusted that as the cam shaft rotates the cam 45 will cause the locking lever 50 to be lifted to free the index plate 53. While the lock 75 is held so disengaged (see Fig. 6) the cam 55 will cause the arm 64 to move the index plate forward one step when it will be again locked by the member 50. The arm 64 may now return with its pawl 65 ready for another stroke for the next advance of the index plate.

Rotating between the die heads 19 and 20 is a roulette wheel 67 mounted on the shaft 54. The roulette wheel 67 acts as a blank carrier and has in its periphery as many blank holding sockets as there are slots in the periphery of the index plate 53 and the arrangement is such that each stepped movement of the index plate will bring a new blank between the die heads 19 and 20 and hold it in alignment therewith. The roulette wheel 67 may be built up by providing a disc with peripheral recesses 68 on both sides and then cutting dove-tailed recesses 69 through the remaining central portion. Inserts 70 may be correspondingly dove-tailed to engage the recesses 69 and may be provided with recesses 71 to receive the heads or other projections of bolts or bolt blanks. The particular roulette illustrated is designed for rim bolts such as illustrated in Figs. 12 and 13 having shanks extending in both directions from hexagonal upsets or heads at their middles. As clearly shown in Fig. 9 the insert 70 is provided with a recess 71 shaped substantially to correspond with a hexagonal head so that when the hexagonal head of a bolt is placed in the recess 71 it may be held from turning and the shanks will extend perpendicularly on both sides of the carrier. Between the recesses 69 are radially extending lugs 72 to which may be fastened retaining plates 73 resting in the peripheral recesses 68 and extending across the inserts 70 so as to hold them securely in place. Registering with the recesses 71 and on both sides thereof are recesses 85 in the plates 73 to receive the shanks of bolts placed in the roulette. Other forms of bolt blanks may require other suitable forms of roulette wheels. This mechanism may be sufficient but preferably other and additional means will be employed to center and hold the blanks as pointed out in the next paragraph.

Intermediate the cam shaft 21 and the die shafts 13 and 16 and parallel with them, a longitudinal shaft 74 may be rotatably mounted in bearings in the intermediate

frames 10 and 12. Carried by the shaft 74 threads. Such an arrangement may be desirable especially when a roulette wheel such as is shown in Figs. 14, 15 and 16 is used. The roulette wheel 67^a there shown is adapted to carry groups of two aligned bolt blanks 70 instead of double ended bolt blanks. A continuous central circumferential plate 83 is provided and alinged sockets on each side of the plate are arranged to receive the heads of bolt blanks. The two bolt blanks thus 75 placed with their heads against the central plate 83 will have their shanks extending in opposite directions so as to be operated on by the opposing heads 19 and 20. In this arrangement it may be desirable to provide in the roulette 67^a a lengthened seat 84 adjacent the head for the bolt shank and the holding down lever 75^a may have its fingers broadened to correspond to the lengthened seat 84. In this arrangement I prefer to 80 have the lever 75^a engage the bolt shank above the seat 84 rather than entirely without the roulette. 85

20 Further travel of the blank in the roulette 67 beyond the die heads 19 and 20 causes it to engage a stripper 81 rising from the bed plate 6 and extending on both sides of the roulette wheel 67. The blanks ejected from 25 the roulette wheel by the stripper fall into a chute 82 by which they may be led by gravity from the machine.

The various cams on the shaft 21 are not shown in detail as it is believed that one 30 versed in the art will be able to design suitable cams for any machine incorporating the present invention.

It will be understood that blanks may be placed, by hand or other suitable means, in 35 the roulette wheel which will carry them between the die cutting heads 19 and 20 and into alignment therewith. The blanks will then be grasped and positioned by the lever 75 and the die heads 19 and 20 will be caused to approach each other and substantially simultaneously engage the opposite ends of the blanks. After the dies have 40 grasped the blanks, the lever 75 may release the blanks and withdraw from the 45 path of the die heads and the die heads will proceed to cut threads on the blank until they are opened by engagement of the levers 30 and 41 with the stop nuts 32 and 43 when the cutting heads 19 and 20 will be opened. 50 The heads 19 and 20 will then be withdrawn from the bolts, the roulette wheel will then turn to cause the bolts to engage the stripper and be ejected and at the same time to bring other blanks into position to be operated on by the cutting head.

In the present instance as illustrated in Fig. 11 a right hand thread will be cut on one end of the bolt and a left had thread on the other end of the bolt since both the die 60 heads 19 and 20 rotate in the same direction. It will be obvious, however, to one versed in the art that a twisting of either the belt 15 or the belt 16 will cause the cutter heads 19 and 20 to run in opposite directions and so 65 both cut either right hand threads or left hand

In practice suitable lubricating and other appurtenances may be applied to the device 90 but these are well known in the art and, therefore, it is not essential that any particular type be used so none is shown.

I claim as my invention:—

1. In a machine for threading both ends 95 of bolts having heads at their middle, a disc having sockets in its periphery shaped to receive the heads of the bolts and hold them from turning and recesses at both sides of the sockets to receive the inner ends of the bolt shanks, oppositely disposed aligned thread cutting die heads, means to cause the disc to rotate to bring a blank into alignment with the die heads, and means to cause the die heads to simultaneously approach the blank and to cut threads on both ends thereof at the same time.

2. In a machine for threading both ends 100 of bolts having heads at their middle, a disc having sockets in its periphery to receive the heads of the bolts and recesses at both sides of the sockets to receive the inner ends of the bolt shanks, oppositely disposed aligned thread cutting die heads, means to cause the disc to rotate to bring a blank into alignment with the die heads, means co-operating with the disc to hold a blank when in alignment with the die heads, and means to cause the die heads to simultaneously approach the blank and to cut threads on both ends thereof at the same time.

3. In a machine for threading both ends 105 of bolts having heads at their middle, a disc having sockets in its periphery to receive the heads of the bolts and recesses at both sides of the sockets to receive the inner ends of the bolt shanks, oppositely disposed aligned thread cutting die heads, means to cause the disc to rotate to bring a blank into alignment 110 with the die heads, means to lock the

- disc in such position, means co-operating with the disc to hold a blank when in alignment with the die heads, means to cause the die heads to simultaneously approach the blank and to cut threads on both ends thereof at the same time, and a cam shaft for actuating the disc rotating and locking means, the blank holding means, and the die head operating means.
10. 4. In a machine for threading bolts having heads, a disc having sockets in its periphery shaped to receive the heads of the bolts and hold them from turning and recesses at both sides of the sockets to receive the inner ends 15 of the bolt shanks, oppositely disposed aligned thread cutting die heads, means to cause the disc to rotate to bring blanks into alignment with the die heads, and means to cause both die heads to simultaneously approach the blanks and to cut threads on the blanks at the same time.
5. In a machine for threading bolts having heads, a disc having sockets in its periphery to receive the heads of the bolts and recesses at both sides of the sockets to receive the inner ends of the bolt shanks, oppositely disposed aligned thread cutting die heads, means to cause the disc to rotate to bring blanks into alignment with the die heads, means co-operating with the disc to hold the blanks when in alignment with the die heads, and means to cause both die heads to simultaneously approach the blanks and to cut threads on the blanks at the same time.
6. A disc having annular recesses at its periphery on both sides and dovetailed recesses through the center of the disc at its periphery, inserts engaging the dovetailed recesses and having recesses shaped to engage and hold the head of a bolt blank, and binding pieces in the annular recesses holding the inserts in place and having recesses to receive shanks of bolt blanks.
7. A disc having annular recesses at its periphery on both sides and dovetailed recesses through the center of the disc at its periphery, inserts engaging the dovetailed recesses and having recesses shaped to engage and hold the head of a bolt blank, binding pieces in the annular recesses holding the inserts in place and having recesses to receive shanks of bolt blanks, means for rotating the disc, and means for working on the blanks while in the disc.
8. In a machine for threading both ends 55 of bolts, a carrier to receive the bolts, oppositely disposed aligned die heads, means to cause the carrier to bring a blank into alignment with the die heads, means to grasp a blank on both sides of the carrier, and means 60 to cause the die heads to simultaneously approach the blank and operate on both ends thereof at the same time.

FRANKLIN O. ANDREWS.
